UNITED STATES PATENT OFFICE

NICOLAS EMILIE MÉTHLIN, OF PARIS, FRANCE, ASSIGNOR TO SCHNEIDER & CIE.,
OF PARIS, FRANCE, A LIMITED JOINT-STOCK COMPANY OF FRANCE

DISAPPEARING CARRIAGE FOR GUNS MOUNTED ON BOARD SUBMERSIBLE CRAFT AND
FOR OTHER LIKE USES

Application filed October 15, 1927, Serial No. 226,357, and in France December 18, 1926.

There exist a fairly considerable number of devices fitted to guns mounted on board submersible and other craft, which enable a gun to be made to disappear when it is not in action and, inversely, to be brought back above the ship with a view to carrying out firing.

In the greater part of these known devices the disappearance of the gun is effected by means of levers or arms pivoted, on the one hand on a fixed part and, on the other hand, to the mass to be made to disappear, the effect of which is to produce a multiplication of pivotal joints, the mass to be lowered and raised alternately moving with pivots which are themselves movable.

The disappearing carriage which forms the subject of the present invention comprises in all and for all a single pivot carried by fixed bearings, the mass to be made to disappear being however as small as possible. This result is essentially obtained by dividing the lower carriage or frame into two superposed elements, the upper element forming a crinoline mount or step bearing for the pivot of the top carriage which carries the gun and being pivoted to the lower fixed element carrying the horizontal pivot, about which the whole of the gun is lowered or raised, of the top carriage and of the said upper element or crinoline mount.

These two superposed elements between which, in order to make the disappearance and subsequent righting possible, it is not possible to make a permanent connection, are combined with an engaging or hooking device which permits the element which can be lowered, to be locked upon the fixed element when the gun is raised into its working position and can, on the other hand, be brought into a disengaged position for the operations producing the disappearance and the subsequent righting.

According to a particular embodiment of the invention, the lock between the folding down element of the under-carriage and of the fixed element is obtained by means of a rotatable hooking device having its centre upon the axis of the pivot of the top carriage and adapted to be operated by means of the

mechanism itself by which the pivoting mass is made to disappear and is righted. This righting operation and the hooking operation, as, on the other hand, the disengagement and disappearance, are obtained in a continuous manner by the interposition of a double clutch between the operating member and the two mechanisms to be operated successively.

Such an embodiment of the invention is illustrated by way of example in the accompanying drawing.

Fig. 1 is a sectional elevation of a general arrangement of a disappearing carriage constructed according to the invention and mounted upon a submersible boat, the gun being shown in full lines in its working position and in dot and dash lines in its withdrawn position.

Fig. 2 is a corresponding sectional plan of a part, to a larger scale, taken along the line 2-2 in Fig. 1.

Fig. 3 is a sectional elevation of a part, the section being taken along the line 3-3 in Fig. 2.

Fig. 4 is a sectional elevation of a part, with the section taken along the line 4-4 of Fig. 2.

Fig. 5 is a sectional elevation of a part, the section being taken along the line 5-5 in Fig. 4.

Fig. 6 is a section taken along the line 6-6 in Fig. 4.

Fig. 7 is a similar sectional elevation to that shown in Fig. 4 showing the members in another working position.

Fig. 8 is a plan section of a part similar to that shown in Fig. 2, the members being shown in a different position.

Fig. 9 is a diagrammatic development, showing the hooking device in its disengaged position.

The under-carriage, as shown in Fig. 1, is mounted in the usual manner upon the keelson A of the resisting hull. According to the invention, it comprises two elements, a lower fixed element B suitably secured to the said keelson, and an element C which, in the position of use of the gun, is superposed upon the first; this latter element is formed by a crinoline mount forming a step bearing for

the pivot of the top carriage D of any known type, in which is journalled the cradle E of the gun barrel. The arrangement formed by the element C, the top carriage D and the 5 oscillating mass E is pivoted by the arms C¹ about a shaft F for which bearings are formed upon the fixed element B.

Each of the arms C¹ is preferably rigid with a cam C², on which is adapted to wind a 10 cable or a chain C², one end of which is attached to the said cam while the other end is pivoted to the rod of the piston G of a counterpoise, which comprises an oscillating cylinder H and a spring I pressing at one end 15 upon one of the ends of the cylinder and at the other end upon the piston.

The lowering mechanism comprises no other pivotal connection apart from the shaft F. A locking device is provided between the dropping element C—C¹—C² and the fixed element B. In the form shown, this locking device comprises a sector formed as a projection upon a collar J made in two parts, which is movable in a groove in the 25 fixed element B. The projecting sector is provided with series of notches J¹ adapted to engage, for the locking, with corresponding notches C⁴ formed in projection upon the base of the dropping element C. The collar 30 J—J¹ is provided over a part of its length, corresponding to the sector provided with notches, with helical teeth J² engaging with a driving worm K loosely mounted upon a shaft L which turns in bearings formed upon 35 the fixed element B.

It is immediately seen that by turning the worm K in the desired direction, it is possible to bring the notches J¹ out of engagement with the notches C⁴ and by a movement in 40 the opposite direction, to re-establish the engagement, these teeth J¹ and C⁴ being so shaped as to grip each other after the manner of wedges.

According to the invention, locking and 45 unlocking may be effected by means of the same mechanism which serves for righting and lowering the pivoting part C—D—E. It is this form which is illustrated by way of example in the drawing.

The worm K carries at one end one of the 50 parts K¹ of a dog or other clutch with which a complementary clutch element L¹ formed upon one of the end faces of a sleeve L can be brought into engagement, which sleeve L 55 is provided on its opposite end face with a second clutch element L², this latter element being adapted to be brought into engagement with a complementary element M¹ formed upon a sleeve M which is adapted to slide and turn upon the shaft L. The said sleeve M is adapted to slide in the boss of a pinion N, which forms the driving member of the mechanism for righting and lowering the pivoting mass. In the example shown, this 65 mechanism comprises a bevel pinion N¹

keyed upon one of the ends of a shaft N² which turns in the fixed element B and carries at its other end a worm N³ which engages with a worm wheel N⁴ keyed upon the shaft F. The shaft L is driven by a transmission gear P—P¹—P² terminating in a handle P³, (Fig. 2), which can be operated by a gun servant stationed on the keelson. The same shaft may alternatively be driven through a transmission gear Q—Q¹—Q²—Q³—Q⁴—Q⁵ terminating in a handle Q⁶ (Fig. 1) adapted to be operated from the inside of the hull.

If the gun is assumed to be in the position of use shown in Figs. 1-6 inclusive and if it is desired to make the gun disappear, the handle P³ or the handle Q⁶, as desired, is actuated for this purpose. It will be assumed for example that the operation is effected by means of the handle P³.

The teeth J¹ are superposed upon the teeth C⁴ and the clutch elements L¹ and K¹ are in engagement, while the clutch element L² is disengaged from the clutch element L¹.

The movement of rotation of the handle P³ is transmitted through the pinions P¹ and P to the shaft L and through the clutch sleeve L' mounted upon the square part of this shaft to the element K¹ and consequently to the worm K, which thus drives the collar J in the direction of the arrow (Fig. 2) and brings it into the position shown in Figs. 8 and 9.

Before the locking engagement of the collar J terminates, a heel piece j formed upon the collar J meets one of the arms R of a rocking lever R—S pivoted at r to the fixed element. The other arm S of this rocking lever forms a fork for displacing through the medium of a ring M², the clutch sleeve M—M¹, the dogs of which are thus brought into engagement with the dogs L² of the sleeve L. As soon as the engagement is established between the clutch elements M¹—L², the movement of rotation given to the handle drives, through this engagement, the pinion N and, through the latter the transmission gear N¹—N²—N³—N⁴, consequently the shaft F and with the latter the whole of the pivoting mass C—D—E, which is then disengaged from its attachment upon the fixed element B.

As it will be seen, the single continuous operation of the lever P³ has permitted the pivoting mass to be disengaged, then this disengagement having been effected, this mass to be brought into the lowered position shown in dot and dash lines in Fig. 1.

As long as the upper element C continues to bear upon the element B, that is to say, during the whole unscrewing movement of the collar J, the clutch L—L¹—L² remains longitudinally in the position shown in Figs. 2 and 4. As soon as, during the lowering movement of the pivoting mass, the crinoline mount C leaves its bearing upon the lower element B, a fork T mounted upon a shaft T¹ turning in

the fixed element B is driven by a toothed sector T² keyed upon the same shaft T¹ and displaced under the action of a spring T⁴ by a rack T³ which, until this moment, remains 5 pressed against the crinoline mount C. During this movement, the double clutch L¹—L² is displaced along the shaft L and brought into the position shown in Fig. 7, in which the said clutch is disengaged from the clutch ele- 10 ment K¹ carried by the worm K. It has thus been possible to effect the lowering of the pivoting mass without the worm K having been actuated.

Inversely, when it is desired to return the 15 pivoting mass from its concealed position indicated in dot and dash lines in Fig. 1 into the position of use of the gun, one or the other of the handles P³ or Q⁶ is turned in the opposite direction. In doing this, the pivoting 20 mass is first of all moved by the transmission gear N⁴—N³—N²—N¹—N until the element C reaches the vertical position and takes support upon the lower element B. As soon as 25 this support is established, the rack T³ has become lowered and has compressed the spring T⁴. In its downward movement it moves the fork T by means of the toothed sector T² and thus returns the sleeve L¹—L² from the position shown in Fig. 7 into that 30 shown in Fig. 4, the effect of which will be to permit the worm K to be driven. At the commencement of the locking movement, the heel boss j moves away from the arm R and the rocking lever R—S, thus permitting a return 35 spring S¹ attached at one end upon the element B and tending constantly to raise the arm R, to return the fork R—S into the position shown in Fig. 2; a spring M³ being thus able to return the sleeve M—M¹—M² into 40 the position shown in this same figure and by this means break the coupling engagement between the sleeve L¹—L² and the sleeve M. The continuous turning of the handle P³ permits in this way the pivoting mass to be 45 locked upon the element B by the displacement of the collar J which again wedges or locks the teeth J¹ upon the teeth C⁴.

For completing the locking operation and insuring a perfect connection between 50 the element C, B of the under-carriage, it is possible, as shown in the drawing (Figs. 1, 2, 3), to provide, on the rack C, a sector C⁵ constituting a gripping device upon a corresponding flange provided on the upper part 55 of the fixed element B.

Claims:

1. Apparatus of the class described comprising relatively movable upper and lower carriage parts, a gun operatively mounted 60 on said upper carriage part, and operative connections between said carriage parts permitting relative movement therebetween comprising unitary connecting means rigid with one of said parts and pivotally connected 65 with said other part.

2. Apparatus of the class described comprising relatively movable upper and lower carriage parts, a gun operatively mounted on said upper carriage part, and operative connections between said carriage parts for relative movement therebetween comprising unitary connecting means rigid with said upper part and pivotally connected with 70 said lower part.

3. Apparatus of the class described comprising relatively movable upper and lower carriage parts, a gun operatively mounted on said upper carriage part, means for locking said parts in superposed relation, and operative connections between said carriage parts to permit relative movement therebetween comprising unitary connecting means rigid with one of said parts and pivotally connected 75 with said other part.

4. Apparatus of the class described comprising relatively movable upper and lower carriage parts, a gun operatively mounted on said upper carriage part, means for locking said parts in superposed relation, and operative connections between said carriage parts to permit relative movement therebetween comprising unitary connecting means rigid with said upper part and pivotally connected 80 with said lower part.

5. Apparatus of the class described comprising normally superposed upper and lower gun carriage elements, means operatively connecting said elements for relative movement, means locking said parts in superposed relation, means for moving said parts 85 relative to one another, and common actuating means for said locking means and said moving means.

6. Apparatus of the class described comprising normally superposed upper and lower gun carriage elements, means operatively connecting said elements for relative movement, means locking said parts in superposed relation, means for moving said parts relative to one another, actuating means, and clutch means connecting said actuating means 90 with said locking and moving means.

7. Apparatus of the class described comprising normally superposed upper and lower gun carriage elements, means operatively connecting said elements for relative movement, means locking said parts in superposed relation, means for moving said parts relative to one another, actuating means, and clutch means movable to operatively connect said 95 actuating means alternately with said locking means and moving means.

8. Apparatus of the class described comprising normally superposed upper and lower gun carriage elements, means operatively connecting said elements for relative movement, means locking said elements in superposed relation, means for moving said elements relative to one another, actuating means, clutch means movable to operatively 100

connect said actuating means alternately with said locking means and moving means, and automatic clutch shifting means.

9. Apparatus of the class described comprising normally superposed upper and lower gun carriage elements, means operatively connecting said elements for relative movement, means locking said elements in superposed relation, means for moving said elements relative to one another, actuating means, means movable to operatively connect said actuating means alternately with said locking and moving means, and clutch shifting means operated by movement of one of said actuated means to shift said clutch means to engage the other actuated means.

10. Apparatus of the class described comprising normally superposed upper and lower gun carriage elements, a rotatable locking device maintaining said elements in normal superposed relation, rotating means for said device, means pivotally connecting said elements, means for rotating one of said elements about its pivot, actuating means, a clutch device alternately connecting said actuating means with one of said rotating means, and clutch shifting means operated by one of said rotating means to shift said clutch into engagement with the other rotating means.

11. Apparatus of the class described comprising normally superposed upper and lower gun carriage elements, means operatively connecting said elements for relative movement, a rotatable locking device for maintaining said elements in superposed relation, and continuously operable actuating means for rotating said locking device and said elements.

40 12. Apparatus of the class described comprising normally superposed upper and lower gun carriage elements, means operatively connecting said elements for relative pivotal movement, means locking said elements in superposed relation, and continuously operable common actuating means for said locking means and said connecting means.

In testimony whereof I have signed this specification.

50 NICOLAS EMILIEN METHLIN.
